PROTECTIVE APRON

Elda E. Purdon, Detroit, Mich.

Application October 27, 1949, Serial No. 5,740

Term of patent 3½ years

(Cl. D3—26)

To all whom it may concern:

Be it known that I, Elda E. Purdon, a citizen of the United States of America, residing at Detroit, in the county of Wayne and State of Michigan, have invented a certain new, original, and ornamental Design for a Protective Apron, of which the following is a specification, reference being had therein to the accompanying drawing, forming a part thereof, wherein:

Figure 1 is a front elevational view of a protective apron, showing my new design;

Figure 2 is a side elevational view of the protective apron shown in Figure 1; and

Figure 3 is a rear elevational view of the protective apron shown in Figure 1.

I claim:

The ornamental design for a protective apron, substantially as shown.

ELDA E. PURDON.
